UNITED STATES PATENT OFFICE.

GEORGE A. WILLIAMS, OF DECATUR, ILLINOIS, ASSIGNOR TO THE WILLIAMS SEALING CORPORATION, OF DECATUR, ILLINOIS, A CORPORATION OF CONNECTICUT.

BOTTLE-CAPPING MACHINE.

Application filed September 14, 1918. Serial No. 254,030.

To all whom it may concern:

- Be it known that I, GEORGE A. WILLIAMS, a citizen of the United States, residing at Decatur, in the county of Macon and State of Illinois, have invented a certain new and useful Improvement in Bottle-Capping Machines, of which the following is a full, clear, and exact description, reference being had to the accompanying drawings.
- 10 This invention relates generally to bottle capping machines and more particularly to certain improvements upon the bottle capping machine patented to me July 18, 1916, No. 1,191,258.
- 15 The object of this invention is to improve certain features of the machine disclosed in the aforesaid patent and whereby a simpler and cheaper machine is provided and at the same time one which is more convenient of, 20 and efficient in operation, and with these objects in view the invention consists in the novel features of construction hereinafter fully described and pointed out in the claims.
- In the drawings forming a part of this 25 specification, Fig. 1 is a face view of a machine constructed in accordance with my invention; Fig. 2 is a side view of the same; Fig. 3 is a vertical sectional elevation taken through the upper portion of the device; 30 Fig. 4 is a horizontal sectional view on the line 4—4 of Fig. 3; Fig. 5 is a sectional view on the line 5—5 of Fig. 3; and Fig. 6 is a detail perspective view of the lever turning finger with the pinion for operating the 35 same; Fig. 7 is a front view of plunger and chuck; Fig. 8 is a side view of same; Fig. 9 is a horizontal section on the line 9—9 of Fig. 7; Fig. 10 is a detail perspective view of one of the spring plates of the chuck; 40 Fig. 11 is a perspective view of one size of chuck; Fig. 12 is a similar view of a larger size; and Fig. 13 a perspective view of a modification for use in connection with still larger sized caps.
- 45 In the practical embodiment of my invention I employ an upright standard 10, the lower portion of which is made hollow or of skeleton formation and is provided with a flat base 11 capable of being bolted or otherwise fastened to the floor. The standard at its upper end is formed with an arm or boss 12, and also with an intermediate boss 13, and a lower boss 14, all of said bosses being 50 in vertical alignment. The lower boss 14 is bored to receive a sleeve nut 15 or thrust 55 member through which works the screw shaft 16 carrying a bottle support 17 at its upper end. This support is provided with lateral guide extensions 17^a which embrace the standard and prevent the support turning. A hand wheel 18 is rigidly connected to the upper end of the sleeve nut 15 and by means of which said threaded sleeve or nut can be turned so as to regulate the position of the bottle support 17 in order to accommodate bottles of various heights. A jam nut may be arranged above the hand wheel to lock the same with sleeve upon the screw. The threaded sleeve or nut 15 is 60 operated upon by the bifurcated lever 19 pivoted at 20, the rear member thereof being weighted as shown at 21 in order to maintain the bifurcated forward portion 65 constantly in contact with the lower end of the threaded sleeve or nut, and when the lever 19 is rocked, the sleeve with the threaded shaft is moved upwardly and consequently the bottle upon the support will 70 be raised vertically. The lever is rocked by means of the arm 22 actuated by the treadle 23 mounted upon the rock shaft 24. This shaft 24 projects laterally from both sides of the standard 10, whereas the actuating arm 22 is arranged centrally of the standard 75 as is also the lever 19. By having the shaft 24 of considerable length, and having the ends extend laterally upon opposite sides, it is possible to mount the treadle 23 upon either end, or both ends if preferred, and in 80 Fig. 1 I have shown the machine as equipped 85 with two treadles so that the operator can use both feet. Each treadle is provided with a rest or stop 25 at the free end thereof and into which the heel fits. The treadle 23 is 90 curved as shown, so that, in its normal position the free end thereof extends forward and upwardly and by kicking straight out while the foot is firmly pressed upon said treadle, the operation is rendered quick and 95 easy.
- By having the shaft 24 the proper length the treadle 23 will be so positioned as to be in convenient reach of the operator when sitting directly in front of the machine, which is the correct operative position. If 100 only one treadle is used it can be arranged either upon the right side or left side as the operator may prefer.
- The bottle rests upon the support 17 and 105 is positioned by means of a holder or gauge 110

26 curved or angled to receive various shapes of bottles and having rearwardly extending slotted guide members 27 through which the fastening bolts 28 are passed into the support 17. By means of this construction the bottle holder or guide can be adjusted back and forth so as to properly center any size or shape of bottle, and several sizes of guides may be provided.

10 The boss 13 is bored vertically and faced off to receive the upper portion of the plunger 29, this upper portion being curved to correspond to the bored portion of the boss and the front face thereof is flattened 15 as shown at 30 and a plate 31 is bolted to the boss 13 for the purpose of holding the plunger properly positioned in the boss but at the same time permitting the free and easy vertical movement within the same.

20 A shaft 32 is rigidly fixed in the upper end of the plunger and extends vertically upward through a nut 33 screwed in the threaded bore of the upper boss 12, and surrounding the shaft 32 is a coil spring 34, 25 the upper end thereof bearing against the nut 33 while the lower end thereof bears against a collar 35 rigidly attached to the shaft as indicated in the drawings. The caps to be applied to the bottles are made 30 of sheet metal in accordance with my Patent No. 1,108,959 granted September 1, 1914. These caps embodying a slotted sheet metal skirt, an encircling ring and a wire lever for contracting the ring and skirt upon the 35 mouth of a bottle.

A casting or forging 36 is sometimes bolted to the rear face of the lower portion of the plunger, the lower end of this casting being curved as indicated at 37 to serve as 40 a guide for the bottle. This casting 36 is adapted for use only with the largest size bottle caps and in order to provide for the efficient operation of this machine with smaller sized bottle caps I provide a chuck 45

39. Various types of chucks are shown in Figs. 7-13 inclusive and the smaller sizes thereof can be used in connection with the casting 36 but in some instances the depending guide portion 37 of the casting 36 will 50 be omitted. Each chuck 39 comprises an upper portion which is connected to the lower end of the plunger 29 and a lower portion which serves as a guide for the bottle, and between the upper and lower portions there are openings at each side across which are arranged spring gripping plates 60 which serve to hold the bottle cap in its proper position in the chuck. Each spring plate 60 has an outwardly projecting lip 61 55 at the forward end and also an outwardly extending flange 62 along the lower forward portion, said plate 60 being cut away at 63 intermediate its ends to render the forward portion more resilient. These plates are 60 secured by means of screws 64 extending into

the sides of the chuck. The lip 61 projects inwardly and downwardly as shown in order to prevent any dislocation of the cap after it has once been properly positioned in the chuck. In the construction of chuck shown 70 in Fig. 13 the depending guide portion 39 is omitted and it will be understood that this form of chuck is employed for use in connection with the largest sized bottle caps the caps being held between the spring gripping plates 60, and bottle guided by 37.

The casting 36 has a shaft 42 journaled therein and a stud 43 fixed therein, the shaft 42 having a pinion 44 upon its outer end with which mesh the teeth 45 of the segmental gear 46 pivoted upon the shaft 43. This segmental gear also has teeth 47 which mesh with the rack 48 secured in proper position upon the standard 10. The inner end of the shaft 42 carries the capping finger 49 which is adapted to engage the lever of the bottle cap and throw the same down for the purpose of fastening the cap upon the mouth of the bottle and this operation takes place as the bottle forces the plunger upwardly against the compression of the spring 34. It will be understood that the rack 48 is stationary and consequently the teeth 47 of the segmental gear 46 meshing with this rack will turn the segment so as to operate the pinion 44 by the teeth 45 and the pinion being rigidly mounted upon the end of the shaft 42 will carry the capping finger 49 over and down in the arc of a circle thereby throwing down the lever of the bottle cap 85

and quickly and easily fastening the same upon the mouth of the bottle. The bottle caps are thrown into the hopper 50, fastened at the upper side of the standard 10 and descend into the chute 51 which extends adjacent the chuck. From here they are picked one at a time and inserted by hand into the chuck with the lever of the cap turned up. It will be noted that the lower end of the plunger 29 has a forwardly projecting inclined lip 52 and the upper portions of the chucks 39 which are attached to the lower end of the plunger are also provided with forwardly projecting inclined lips 52^b which coincide with and constitute a continuation 115 of the lip 52 and these forwardly projecting inclined lips are notched centrally as shown at 52^b the purpose of which is to accommodate the upturned lever of the cap. The capping finger 49 normally rests against the forwardly projecting lip as most clearly shown in Fig. 2 and when the cap is properly inserted into the chuck the upwardly projecting lever will rest in the central notch 52^b and will be adjacent to the finger 49. After the cap has been properly inserted, the treadle is operated causing the bottle support with the bottle thereon to be moved upwardly and this bottle being properly centered by contacting with the rest 26 the 120 125 130

mouth of the bottle will be directed into the bottle cap which is securely held in the chuck by means of the spring plates 60 and the continued upward motion of the support 5 will cause the chuck and plunger to be moved upwardly against the compression of the spring and the shaft 42 being rotated as previously described causing the capping finger to engage the lever and turn the same down 10 completing the capping operation. By the employment of different sized chucks I am able to use one machine for applying all sizes of bottle caps.

By having the boss 13 open at the front, 15 an easy method of inserting and removing the plunger is provided, and at the same time the plate 31 bearing against the flat face of the plunger maintains said plunger and chuck in a perfectly true position at all 20 times. In practice I prefer to employ a guard housing 56 which is attached to the casting 36 for the purpose of enveloping the pinion, segment and rack and thereby eliminate the danger of the operator getting 25 a finger caught in the gearing during the operation of the machine.

It will thus be seen that I provide an improved construction of bottle capping machine which can be operated from either side 30 of the machine or from both sides of the machine at the same time and one in which

certain of the parts are interchangeable thus giving the machine as a whole a more extended usefulness.

Having thus described my invention, 35 what I claim is:

1. In a bottle capping machine, the combination with a standard, of a bottle support having guiding extensions embracing a portion of said standard, a screw shaft, a 40 threaded nut through which said shaft passes, said threaded nut being movable vertically in the standard, a hand wheel connected to the upper end of said threaded nut, a bifurcated lever adapted to straddle the 45 threaded shaft and engage the lower end of said threaded nut, a transverse rock shaft, a centrally disposed arm upon said shaft adapted to engage said lever, and a curved treadle upon either end of said rock shaft as 50 set forth.

2. A chuck comprising upper and lower portions, said upper portion having a forwardly projecting lip, said lip having a central notch, and spring plates attached to 55 the sides of the chuck between the upper and lower portions, said plates being secured at the rear ends, their forward ends being resilient.

In testimony whereof, I hereunto affix my 60 signature.

GEORGE A. WILLIAMS.
